UNITED STATES PATENT OFFICE

JACOB FRIEDMAN, OF NEW YORK, N. Y.

LOCK

Application filed September 26, 1929. Serial No. 395,389.

This invention relates to locks, the general object of the invention being to so form the lock that it will be practically burglar proof by making the locking bolt hook shaped so 5 they will make a positive connection with the keeper.

Another object of the invention is to provide a lock of the general type indicated above which shall be of simple construction and 10 positive in operation, which shall be adapted to be applied to either a swinging or a sliding door and which shall be so constructed as to effectively prevent an unauthorized entrance through the door.

15 Other objects will appear as the disclosure progresses. The drawings are intended merely to indicate a possible embodiment of the invention. It is obvious that the needs of manufacture may necessitate certain mechanical changes. It is therefore not intended to 20 limit the invention to the embodiment illustrated but rather to define such limits in the appended claims.

25 In brief the invention mainly consists of a sliding plate or bolt actuator to which are pivoted a pair of hooked bolts which engage or disengage with the keeper when the key or knob is turned.

30 For a more general understanding of the invention attention is called to the drawings. In these drawings like numerals indicate like parts throughout the specification.

Figure 1 is a sectional view of the lock and keeper showing them disengaged from each 35 other.

Figure 2 is a similar view as Figure 1 but with the bolts partly in a locked position.

Figure 3 is another view similar to Figure 1 but showing the bolts in a fully locked position.

Figure 4 is a section on line 4—4 of Figure 1.

Figure 5 is a section on line 5—5 of Figure 2.

45 Referring now to the drawings in detail numeral 1 designates the casing for the lock which may be bolted on the door or other structure to be opened and 2 the keeper attached to a stationary part of a building.

50 Within the casing is sliding bolt actuator 3

supported by the slides 4 and 5. Pivoted to the bolt actuator on the pins 6 and 7 are two hook shaped bolts 8 adapted to engage with boss 9 of the keeper. Also pivoted to the pins 6 and 7 and normally resting on the support 10 is a lever 11. The pins 6 and 7 are permanently attached to the bolt actuator 3 but however the bolts 8 and lever 11 are loosely and pivotally mounted thereon.

As noted in Figures 4 and 5 a cylinder lock 60 12 is mounted in the door and held in place by any suitable means. The cylinder lock has the usual key opening with which the key 13 is inserted for rotating the key plug 14 and operating the lock. This cylinder 65 lock may be of any appropriate design such as is now used in conventional locks. Fixed to the key plug 14 are two cam arms 15 and 16 which alternately engage and disengage with a slot 17 formed in the bolt actuator 3. 70 The bolt actuator 3 is slotted as at 18 in order to clear the locking lug 10 when the said actuator slides on its supports.

The neutral position of the cam arms 15 and 16 is as shown in Figures 1 and 3. To 75 retain the arms in this position a pair of springs 19 are provided which bear against the periphery of the key plug 14. Cut in the periphery of the key plug are two flattened portions 20.

80 When the ends of the springs come in contact with the said flattened portions the key plug will be locked in place and any accidental turning will be prevented.

Attached to the key plug 14 and extending 85 outward of the casing 1 is a knob 21 for actuating the cams 15 and 16. This knob is directly opposite the cylinder lock 12. As noted in Figures 3, 4 and 5 the key is adapted to enter the end of the key plug 14. It will 90 thus be apparent that the key plug can be revolved by the key on the outside of the door or by the knob on the inside of the door.

The operation of this device is as follows. 95 As shown in Figure 1 the device is in the unlocked position. To lock the door the key or knob is turned until the cam arm 16 lifts the lever 11 as shown in Figure 2 thereby disengaging the notch 22 of the lever from the locking lug 10. At the same time the 100

cam arm 16 will move the bolt actuator 3 and the parts associated therewith towards the keeper. The hook shaped bolts 8 will then pass through the openings 23 of the casing and envelop the boss 9 as shown in Figure 3. When it has reached this position the lever 11 will drop down until the notch 24 will register with the locking lug 10 and thereby hold the lever, bolt actuator and its associated parts in place until the lock is further actuated by the knob or key. To keep the lever 11 normally in a horizontal position a torsion spring 25 is provided. One end of the spring is attached to the pivoting point of the lever while the opposite end is fastened to a lug 26 attached to the bolt actuator. While the movement of the bolt actuator 3 is in a horizontal plane the hook shaped bolts will describe a circular or enveloping movement when the bolt actuator is moved towards the keeper. This is due to the curvature of the bolts when passing through the openings 23 which are just wide enough to guide the bolts. Numeral 27 designates the various screws for holding the device in place and 28 an inside detachable cover plate for having access to the mechanism.

It will thus be seen that I have provided a simple efficient lock which can easily be attached and can be used for hinged or sliding doors. The shape of the bolts or locking ends makes for an efficient type of lock for the reason that the said bolts when engaging the boss of the keeper, act as hooks and are not easily displaced. Also when in a locked position the bolts are concealed and protected so that tampering with the lock is extremely difficult. Furthermore the employment of a plurality of bolts of this construction which are movable independently of each other is desirable for the reason that an entrance through the door cannot be gained by merely forcing one of the locking bolts from its engagement with the keeper as that in no wise affects the locking position of the other locking bolt which must also be forced out of its locking position before the door may be opened.

The lever 11 is provided with a double set 50 of notches 22 and 24 which register alternately with the locking lug 10. By this arrangement the bolts 8 cannot be moved unless the lever 11 is raised by the turning of the key or knob.

Having described my invention, I claim:

1. In a lock of the class described comprising a casing, a keeper, a bolt actuator slidably supported in said casing, a pair of pivots attached to the forward part of said bolt actuator, one of said pivots having attached thereto a hook shaped bolt, the other of said pivots having attached thereto a co-operating hook shaped bolt and a lever, said lever having a pair of notches which correspond to the locked and unlocked positions of the

bolts, a locking lug which engages with said notches for preventing any accidental movement of the bolt actuator, and a pair of cams for moving said bolt actuator.

2. In a lock of the class described comprising a casing, a keeper, a bolt actuator slidably supported in said casing, a pair of pivots attached to the forward part of said bolt actuator, one of said pivots having attached thereto a hook shaped bolt, the other of said pivots having attached thereto a co-operating hook shaped bolt and a lever, said lever having a pair of notches which correspond to the locked and unlocked positions of the bolts, a locking lug which engages with said notches for preventing any accidental movement of the bolt actuator, and a pair of cams for simultaneously lifting one end of said lever and moving said bolt actuator.

3. In a lock of the class described comprising a casing, a keeper, a bolt actuator slidably supported in said casing, a pair of pivots attached to the forward part of said bolt actuator, one of said pivots having attached thereto a hook shaped bolt, the other of said pivots having attached thereto a co-operating hook shaped bolt and a lever, said lever having a pair of notches which correspond to the locked and unlocked positions of the bolts, a locking lug which engages with said notches for preventing any accidental movement of the bolt actuator, and a pair of cam arms for contacting at the same time with said lever and said bolt actuator for lifting said lever and moving said bolt actuator simultaneously.

4. In a lock of the class described comprising a casing, a keeper, a bolt actuator slidably supported in said casing, a pair of pivots attached to the forward part of said bolt actuator, one of said pivots having attached thereto a hook shaped bolt, the other of said pivots having attached thereto a co-operating hook shaped bolt and a lever, said lever having a pair of notches which correspond to the locked and unlocked positions of the bolts, a locking lug which engages with said notches for preventing any accidental movement of the bolt actuator, a pair of cams for moving said bolt actuator, a pair of flattened portions in said cams, and a pair of springs which engage said flattened portions and normally keep said cams in a horizontal position.

5. In a lock of the class described comprising a casing, a keeper, a bolt actuator slidably supported in said casing, a pair of pivots attached to the forward part of said bolt actuator, one of said pivots having attached thereto a hook shaped bolt, the other of said pivots having attached thereto a co-operating hook shaped bolt and a lever, said lever having a pair of notches which correspond to the locked and unlocked positions of the bolts, a locking lug which engages with said notches

for preventing any accidental movement of the bolt actuator, a pair of cams for simultaneously lifting one end of said lever and moving said bolt actuator, a pair of flattened portions in said cams, and a pair of springs which engage said flattened portions and normally keep said cams in a horizontal position.

6. In a lock of the class described comprising a casing, a keeper, a bolt actuator slidably supported in said casing, a pair of pivots attached to the forward part of said bolt actuator, one of said pivots having attached thereto a hook shaped bolt, the other of said pivots having attached thereto a co-operating hook shaped bolt and a lever, said lever having a pair of notches which correspond to the locked and unlocked positions of the bolts, a locking lug which engages with said notches 20 for preventing any accidental movement of the bolt actuator, a pair of cam arms for contacting at the same time with said lever and said bolt actuator for lifting said lever and moving said bolt actuator simultaneously, a pair of flattened portions in said cams, and a pair of springs which engage said flattened portions and normally keep said cams in a horizontal position.

In testimony whereof I affix my signature.

JACOB FRIEDMAN.
